UNITED STATES PATENT OFFICE

OSSIAN K. MITCHELL AND LEONARD O. MITCHELL, OF OAK PARK, ILLINOIS

DESIGN FOR A FLOOR READING STAND

Application filed December 26, 1931. Serial No. 42,223. Term of patent 14 years.

To all whom it may concern:

Be it known that we, OSSIAN K. MITCHELL and LEONARD O. MITCHELL, citizens of the

United States, residing at Oak Park, in the county of Cook and State of Illinois, have invented a new, original, and ornamental Design for Floor Reading Stands, of which the following is a specification, reference being had to the accompanying drawing, forming part hereof, wherein—

Figure 1 is a front elevation, and Figure 2 a side elevation of a floor reading stand embodying our new design.

We claim:

The ornamental design for a floor reading stand as shown.

OSSIAN K. MITCHELL.
LEONARD O. MITCHELL.
